UNITED STATES PATENT OFFICE.

ROBERT E. ALDREDGE, OF PLEASANT HILL, LOUISIANA.

JEWEL-SETTER.

1,253,116.

Specification of Letters Patent.

Patented Jan. 8, 1918.

Application filed May 24, 1917. Serial No. 170,745.

To all whom it may concern:

Be it known that I, ROBERT E. ALDREDGE, a citizen of the United States, residing at Pleasant Hill, in the parish of Sabine and State of Louisiana, have invented certain useful Improvements in Jewel-Setters, of which the following is a specification, reference being had therein to the accompanying drawing.

10 The invention relates to a watchmaker's or repairer's tool and more particularly to the class of jewel setters.

The primary object of the invention is the provision of a device of this character 15 wherein a jewel can be accurately set in the roller table of a watch without the removal of said table from the balance wheel journal or the removal of the hair spring or subjecting the hair spring to heat from 20 a flame when applied in the setting of said jewel within the roller table.

Another object of the invention is the provision of a device of this character wherein the construction thereof is novel in form to 25 permit the convenient and easy setting of a jewel within the roller table for a watch, thus avoiding the disassembling of the table, the hair spring, the journal and the balance wheel as is usual.

30 A further object of the invention is the provision of a setting device of this character which is simple in construction, thoroughly reliable and efficient in its purpose, handy in use and inexpensive in manufacture.

35 With these and other objects in view the invention consists in the features of construction, combination and arrangement of parts as will be hereinafter fully described, 40 illustrated in the accompanying drawing and pointed out in the claims hereunto appended.

In the accompanying drawing:

45 Figure 1 is a perspective view of a jewel setter constructed in accordance with the invention;

Fig. 2 is an end elevation showing the device applied;

Fig. 3 is a top plan view.

50 Similar reference characters indicate corresponding parts throughout the several views in the drawing.

Referring to the drawing in detail the tool or device comprises a pair of levers 5 and 6 respectively, each having fitted upon one end thereof a handle 7. The lever 5 is

of less length than the lever 6 and is supported for rocking movement upon a pivot 8 between ears 9 of a bearing strap 10 which embraces the lever 6 and is fast thereon, the 60 pivot 8 being mounted in the ears 9, while fixed to said lever 6 and working against the lever 5 is a leaf spring 11 which normally holds the handle ends of said lever separated and their opposite ends together. 65 The length of the lever 5 relative to the length of the lever 6 permits the convenient manipulation of both levers by the fingers of the hand of the operator in the use of the tool or device in a manner hereinafter set 70 forth.

On the free end of the lever 5 at the inner side thereof is secured a short length plate 12 which constitutes a jaw and this plate lies transversely relative to the length of the 75 lever 5 and is formed with an outwardly tapered end 13 while provided centrally in the tapered end 13 is a substantially V-shaped slot 14 which extends longitudinally of the plate and provides a space or gap for 80 accommodating the journal A of the balance wheel B on one side of which is located the hair spring C while on the opposite side is the roller table D as usual of a watch mechanism. Mounted on the free end of the lever 85 6 transversely thereof relatively to its length is a plate 15 which is of considerably greater length than the plate 12 and constitutes a companion jaw for co-action with the jaw constituted by the plate 12, and this 90 plate 15 is formed with a tapered end 16 correspondingly to the tapered end 13 of said plate 12 and has provided therein a substantially V-shaped slot 17 which is centrally located and extends longitudinally of 95 the plate 15, the said slot 17 being in register with the slot 14 and is designed to accommodate the journal A for the balance wheel B, the tapered end 16 of the plate 15 being gradually beveled at opposite faces so as to 100 render the same relatively thin at the wider end of the slot 17 so that the tapered end 16 of said plate 15 can be freely inserted between the balance wheel B and the roller table D on the journal A supporting the 105 same and especially when the space between the balance wheel and the roller table is considerably restricted as is the case of watch mechanism of certain makes.

Fixed in the plate 15 and working through 110 a suitable hole 18 in the plate 12 is a guide pin or lug 19 which prevents the displace-

ment of the plates 12 and 15 relatively to each other when the levers are operated for the separation of the plates 12 and 15 or the approach of the same toward each other 5 in the use of the tool or device.

Mounted on the lever 6 immediately at one side of the plate 15 thereon and extending at right angles thereto is a guard wing or plate 20 which prevents a flame from a lamp 10 playing upon either the balance wheel or the hair spring when in the act of heating shellac or cement upon the roller table D in the setting of the jewel therein. The plate 15 is preferably made from copper so as to retain heat when a flame from a lamp is played thereon and this plate constitutes a heat carrier so that heat therefrom will be transferred to the roller table D which as usual is provided with a hole or aperture for receiving the jewel E, the latter being in a pin form and is set by the hardening of shellac or cement which is applied by the introduction thereof into the hole or aperture for the jewel E.

25 In the use of the tool or device when it is desired to accurately set the jewel E in the roller table D without removing the roller table from the journal A for the balance wheel B or the removal of the hair spring 30 C from said journal the user of the tool or device compresses the handles 7 on the levers 5 and 6 to lock the lever 5 relatively to the lever 6 against the action of the spring 11 and in this manner the jaws 12 and 15 are separated whereupon the jaw 15 at its tapered end 16 is inserted in the space between the balance wheel B and the roller table D and thereafter pressure is relieved from the levers so that the jaw 12 will rest against 35 the top face of the roller table D and will co-act with the jaw 12 for the clamping of said roller table. The slots 14 and 17 in the respective jaws provide space for accommodating the journal A carrying the 40 balance wheel B, hair spring C and roller table D, it being of course understood that these parts have been previously removed from the frame of the watch structure. In the clamping of the roller table D between 45 the plates 12 and 15 it is necessary that the aperture or hole in said roller table will be exposed at the wider ends of the slots 14 and 17 so that the jewel E can be readily inserted in the hole or aperture in the use of 50 tweezers.

55 Now when the roller table D has been clamped, the operator of the tool or device applies the flame from an alcohol lamp on to the tail or heel end of the plate 15 which latter becomes heated and said flame is pre-

vented from playing upon the balance wheel B and hair spring C by the guard plate 20, and the heat from the plate 15 is transferred to the roller table D so that shellac or cement which is placed within the aperture or 65 hole for the jewel becomes softened thereby enabling the accurate and proper setting of the jewel E within the hole or aperture in said roller table. On the hardening of the shellac or cement the jewel E is made fast 70 in the roller table. Thus in the use of the tool it will be obvious that the jewel E can be readily set in the roller table D without removing the roller table from the journal A or the removal of the balance wheel or 75 hair spring which is usually necessary in the setting of the jewel in the roller table.

From the foregoing it is thought that the construction and manner of operation of the device will be clearly understood and therefore a more extended explanation has been omitted.

What is claimed is:

1. A device of the character described comprising a pair of pivotally connected 85 levers, plates secured transversely to the respective levers and having companion tapered ends each formed with a central bifurcation providing a slot, one of said plates being longer than the other, a guard depending at right angles to the longer plate and carried by the lever supporting the same, means resiliently acting upon the levers to hold the plates normally together, and a guide pin mounted in one of the plates 90 and loosely working through the other plate to prevent relative displacement of the plates when moving toward and away from each other.

2. A device of the character described 100 comprising a pair of pivotally connected levers, plates secured transversely to the respective levers and having companion tapered ends each formed with a central bifurcation providing a slot, one of said plates 105 being longer than the other, a guard depending at right angles to the longer plate and carried by the lever supporting the same, means resiliently acting upon the levers to hold the plates normally together, a 110 guide pin mounted in one of the plates and loosely working through the other plate to prevent relative displacement of the plates when moving toward and away from each other, and one of said levers being of greater 115 length than the other.

In testimony whereof I affix my signature.

ROBERT E. ALDREDGE.
